US00D904887S

(12) **United States Design Patent** (10) **Patent No.:** **US D904,887 S**
Habig et al. (45) **Date of Patent:** **** Dec. 15, 2020**

(54) **BOTTLE**

(71) Applicant: **TARGET BRANDS, INC.**,
 Minneapolis, MN (US)

(72) Inventors: **Michael M. Habig**, Cincinnati, OH
 (US); **Nicholas Cyr**, Minneapolis, MN
 (US); **Richard P. Riedel**, Minneapolis,
 MN (US); **Jeremy Berghoff**, Excelsior,
 MN (US)

(73) Assignee: **TARGET BRANDS, INC.**,
 Minneapolis, MN (US)

(**) Term: **15 Years**

(21) Appl. No.: **29/706,039**

(22) Filed: **Sep. 17, 2019**

(51) LOC (12) Cl. **09-01**

(52) U.S. Cl.

(57) **CLAIM**

The ornamental design for a bottle, as shown and described.

DESCRIPTION

FIG. 1 is a top, front perspective view of a bottle, showing our new design;

FIG. 2 is a bottom, rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

In the drawings, the broken lines depict unclaimed subject matter only and form no part of the claimed design.

1 Claim, 6 Drawing Sheets
